(57) **CLAIM**

The ornamental design for a computer mouse, as shown and described.

DESCRIPTION

FIG. 1 is an upper rear perspective view of a computer mouse showing my new design.

FIG. 2 is a top view of a computer mouse showing my new design.

FIG. 3 is a bottom view of a computer mouse showing my new design.

FIG. 4 is a front view of a computer mouse showing my new design.

FIG. 5 is a rear view of a computer mouse showing my new design.

FIG. 6 is a right view of a computer mouse showing my new design; and,

FIG. 7 is a left view of a computer mouse showing my new design.

Any shading and cross-hatching are not features of the design but are utilized to illustrate the surface contours of the computer mouse in the drawings.
